CLAIM

The ornamental design for a recoil buffer for Glock's, as shown and described.

DESCRIPTION

FIG. 1 is a front view of the recoil buffer for Glock's.

FIG. 2 is a rear view of the recoil buffer for Glock's.

FIG. 3 is a top view showing the recoil buffer for Glock's.

FIG. 4 is a bottom view of the recoil buffer for Glock's.

FIG. 5 is a right side view of the recoil buffer for Glock's.

FIG. 6 is a left side view of the recoil buffer for Glock's.

FIG. 7 is a rear perspective view, on a reduced scale, of the recoil buffer for Glock's; and,

FIG. 8 is a front perspective view, on a reduced scale, of the recoil buffer for Glock's.
